BONING KNIFE

Walter P. Fenner, St. Louis, Mo.

Application January 29, 1940, Serial No. 316,062

1 Claim. (CL 30—144)

This invention relates to a certain new and useful improvement in boning tools or knives.

The invention has for its object the provision, as a new article of manufacture, of a tool in the form of a suitably handled blade uniquely toothed, edged, and shaped for especially, though not exclusively, the facile boning of so-called "hams."

The invention has for a further object the provision of a tool or knife of the type and for the purpose stated which is simple in structure, which may be cheaply manufactured, which is conveniently usable, and which is exceedingly efficient in the performance of its intended functions.

And with the above and other objects in view, my invention resides in the novel features of form, construction, arrangement, and combination of parts presently described and pointed out in the claim.

In the accompanying drawing—

Figure 1 is a plan or edge view of the boning tool or knife of my invention;

Figure 2 is a side elevational view of the knife;

Figure 3 sectionally pictures a "ham" for "boning"; and

Figure 4 shows a section of the ham from which removal of the bone has been effected through employment of the knife of my invention.

Referring now more in detail and by reference characters to the drawing, which illustrates a preferred embodiment of my invention, the boning knife initially includes a suitably elongated substantially oblong-rectangular strip of suitable metal shaped to integrally comprise a blade A and a longitudinal extension B, to which latter a suitable handle C is riveted or otherwise permanently fixed, the blade A and its handled portion or shank B being sized for convenient manual manipulation.

Along one longitudinal margin, the blade A is ground to, or otherwise formed with, a sharp cutting edge 1, and along its opposite longitudinal margin, the blade A is suitably provided with a series of saw-teeth 2, all of which are disposed in the same longitudinal plane and slope or incline in the same direction, somewhat in the nature of a rip saw.

At its free end and forwardly from its opposite longitudinal margins, the blade A is suitably ground to, or otherwise formed with sharp edges 1a and 3, which converge into a relatively sharp point, as at 4, presented forwardly in a plane approximately midway between the planes of the edge 1 and teeth 2, the edge 1a being preferably

gently lengthwise rounded and merging into or being continuous with the edge 1 and the edge 3 obliquely connecting or joining the teeth 2 and point 4, all as best seen in Figure 2.

5 Now, in use, as in boning the "ham" H illustrated in Figure 3, a transverse kerf, as at K, is first made in the ham by means of the cutting edge 1, such kerf K being located adjacent, and extending merely down to, an intermediate or second bone knuckle 5, as shown. The tool is then removed from the "ham" and reversed upon itself, and through employment of the toothed edge 2 of the blade, the kerf K is completed through the bone 7, the cutting-edges 1, 1a, and 3 of the knife greatly facilitating the undulations and reciprocations of the blade A in the relatively soft meat of the ham H in and during such bone cutting operation actual bone cutting being effected only on the so-called forward strokes of 10 the blade through and relatively to the ham H.

Then, by the cutting-edge 1, a second kerf K' is transversely made in the ham H in suitably spaced relation to the first kerf K and more or less adjacent the end or first bone knuckle 6, as 15 also shown. Then the tool is reversed upon itself, and again through employment of the toothed edge 2 of the blade, the kerf K' completed through the bone 7, as indicated, the cutting-edges 1, 1a and 3 again greatly facilitating 20 the undulations and reciprocations of the blade A in the relatively soft meat of the ham H in and during such bone cutting operation and actual bone cutting likewise being effected only on the so-called forward strokes of the blade 25 through and relatively to the ham H.

The bone 7 being thus divided along the kerf K', the end-portion *h* of the ham is totally severed from the remaining portion thereof. Then, on sufficient separating end pull being applied upon the severed or divided bone-portion 30 *x*, the remaining portion *h'* of the ham H is entirely relieved from the bone 7 and may then be easily and profitably sliced for consumption.

Thus my new blade fulfills in every respect 35 the objects stated, and it is to be understood that changes in the form, construction, arrangement, and combination of the several parts of the knife may be made and substituted for those herein shown and described without departing from the nature and principle of my invention.

Having thus described my invention, what I claim and desire to secure by Letters Patent is—

As a new article of manufacture, a boning-knife including an approximately oblong-rectangular blade flat and smooth upon its opposite

side faces and provided with a cutting-edge along one longitudinal margin, a series of saw-teeth along its opposite longitudinal margin, and a cutting point in its forward end approximately centrally intermediate the longitudinal planes of said edge and teeth, said longitudinal cutting-edge being uninterruptedly joined to, and com-

municating with, said point in a gently rounded cutting-edge continuation and said teeth being set in the direction of, and by an obliquely disposed cutting edge oppositely joined to and communicating with, said point.

5

WALTER P. FENNER.
